UNITED STATES PATENT OFFICE.

JOSEPH P. LAVIGNE, OF DETROIT, MICHIGAN, ASSIGNOR TO THE LAVIGNE MANUFACTURING COMPANY, OF DETROIT, MICHIGAN, A CORPORATION OF MICHIGAN.

PUMP.

No. 857,004.

Specification of Letters Patent.

Patented June 11, 1907.

Application filed February 12, 1906. Serial No. 300,600.

To all whom it may concern:

Be it known that I, JOSEPH P. LAVIGNE, a citizen of the United States, residing at Detroit, county of Wayne, State of Michigan, have invented a certain new and useful Improvement in Pumps; and I declare the following to be a full, clear, and exact description of the same, such as will enable others skilled in the art to which it pertains to make and use the same, reference being had to the accompanying drawings, which form a part of this specification.

This invention relates to pumps; it has for its object an improved pump of which the capacity per stroke is adjustable and variable, and has connected with it an indicating device, which shows the capacity to which the pump cavity has been adjusted.

The pump barrel and the immediate actuator for the pump piston are preferably submerged in a tank which contains the supply of liquid to be moved. The pump shown in the drawing is of small capacity and is of the character intended to be used for furnishing a regular and constant supply of oil to machinery to be lubricated. The usefulness of the pump is not, however, intended to be limited to this purpose.

In the drawings:—Figure 1, is an elevation showing two individuals of a battery of pumps submerged in a tank; the tank is shown in section and one of the piston guides is shown in section. Some other parts of the driving mechanism are also in section. Fig. 2, is an elevation of a pump piston. Fig. 3, is an end view of the pump piston. Fig. 4, is an elevation of a guide and indicator.

1, indicates the case of a tank in which the pumps are submerged; in the structure there are assembled several pumps, two of which are shown in the drawing and a description of a single one will suffice for an understanding of all.

2, indicates a casing which includes a pump barrel and a valve shell; 3, indicates an oscillating valve actuated by lever 4, which is pivotally connected to a reciprocating driving rod 5; this driving rod 5 is actuated by cam 6 and a similar cam at the opposite end of the shaft 7 (the second cam is not shown). A piston 8 reciprocates in the barrel 2, and is driven in its reciprocating motion by a cross beam 9 which, itself, is reciprocated by a crank arm 10 pivoted to crank pin 11 on the face of a driving wheel

12. The driving wheel 12 is a worm wheel driven by worm 13 from any convenient source of motion. The beam 9 engages on a prismatic portion 14 of the piston stem and engages between a collar 15 that is fixed 60 with respect to the piston, and a sleeve 16 that is adjustable with reference to the piston. The portion of the stem above the prismatic section 14 has a threaded section 17 with which the sleeve engages, and the 65 sleeve is interiorly threaded in order that it may be adjustable along the threaded portion 17 of the piston stem. The sleeve is also split and engages tightly by resilient compression against the threaded part of the 70 stem.

The sleeve reciprocates through an opening 18 in the case and at its upper end is formed with a prismatic portion 19 to furnish a wrench hold, and above the prismatic portion is a graduated collar 20. The position of the sleeve on the stem is indicated by these graduations, which act in conjunction with ring graduations 21 on the piston stem to indicate the relative position of the sleeve 80 and the piston, and upon this relative position of the sleeve on the piston depends the travel of the piston produced by the cross beam 9. The graduations on the collar 20 indicate portions of a revolution of a sleeve 85 16 relative to the piston stem and the ring graduations 21 indicate the number of such revolutions.

In operation, the cam 6 is timed with reference to the wrist pin 11 to open the conduit controlled by valve 3 during that period of the up stroke of the piston which follows the engagement between the cross beam 9 and the sleeve 16 and to close the valve 3 as the cross beam begins to descend, and to 90 open the conduit for the discharge of the oil from the pump barrel just prior to the time of contact between the cross beam and collar 15 and to keep the discharge open during the period which follows the first contact of the cross beam 9 with the collar 15 on its down stroke. The length of the stroke of the piston which determines the amount of discharge at each impulse is regulated by the position of the sleeve 16 on the piston stem. 95 As shown in the drawing, the sleeve 16 is turned entirely down on the piston stem and the piston in this position with reference to the sleeve will produce its maximum stroke and a maximum flow of oil. 100 105 110

What I claim is:—

1. In a pump, the combination of a pump barrel, a piston reciprocating therein, a stem for said piston provided with a prismatic section, a sleeve adjustable along said piston stem by turning relative thereto, means fitting upon the prismatic portion of the stem for actuating said piston, and means whereby the relative position of said sleeve and stem determines the travel of the piston substantially as described.
2. The combination of a tank, a pump inclosed therein provided with a barrel, a piston and a stem therefor extending through a wall of said tank provided with a prismatic section and with a graduated terminal, a cross-head fitting upon said prismatic section and adapted to slide thereupon, means for reciprocating said cross-head, a sleeve adjustable along said piston stem and extending through the wall of said tank and provided with a graduated terminal adapt-

ed to coact with the graduated terminal of the stem to indicate the travel of said stem, and means whereby the relative position of said sleeve and stem determines the travel of the piston, substantially as described. 25

3. The combination of a tank, a pump inclosed therein, said pump being provided with a piston and stem therefor, said stem 30 extending through a wall of the tank, a sleeve surrounding said stem passing, and adapted to reciprocate through, the wall of said tank, said sleeve being adjustable along said stem, and means whereby the relative 35 position of said sleeve and stem determines the extent of travel of the piston.

In testimony whereof, I sign this specification in the presence of two witnesses.

JOSEPH P. LAVIGNE.
